UNITED STATES PATENT OFFICE.

LAURITZ ANDERSON, OF CHICAGO, ILLINOIS, ASSIGNOR TO HERMAN SONNTAG, OF NEW YORK, N. Y.

BANJO.

SPECIFICATION forming part of Letters Patent No. 248,979, dated November 1, 1881.

Application filed December 31, 1880. (No model.)

To all whom it may concern:

Be it known that I, LAURITZ ANDERSON, a citizen of the United States, residing at Chicago, in the county of Cook and State of Illinois, have invented new and useful Improvements in Banjos, of which the following is a specification.

This invention relates to improvements in banjos; and it consists, essentially, in a mute or echo attachment, inclosed by the surrounding frame and arranged beneath the inside surface of the head of the banjo, said mute or echo attachment being normally retained away from the inner surface of the head by the action of a spring, and having an arm extending outside the banjo-frame with its free disconnected end adapted to be depressed by pressure against the body of the performer.

Other features of the invention will be hereinafter described in detail, and specifically pointed out in the claims.

This invention is illustrated in the accompanying drawings, in which Figure 1 represents an inverted plan of my banjo. Fig. 2 is a longitudinal vertical section of the same. Fig. 3 is a transverse section in the plane $x x$, Fig. 2. Fig. 4 is a vertical section of the rim on a larger scale than the previous figures.

Similar letters indicate corresponding parts. In the drawings, the letter A designates the head of a banjo, which is secured to a ring, B, that fits over the rim C in the usual manner. In the interior of the rim C is firmly secured a bar, D, which forms the bearing for a two-armed lever, $a b$, one arm, b , of which carries a damper, E, and is exposed to the action of a spring, c , that throws the damper off from the inner surface of the head A, and has a tendency to retain the arm a in the position shown in Fig. 2—that is to say, in such a position that the free end of said arm a projects beyond the rear edge of the rim C. The damper E is so situated that when the arm a is pressed inward, said damper bears against the inner surface of the head just beneath the bridge F.

In playing the performer holds the inner edge of the rim close up to his body, allowing the damper-lever $a b$ to assume the position shown in Fig. 2, but if he desires to deaden

the sound and to produce the effect of an echo, 50 he presses the banjo up against his body, so as to force the arm a of the damper-lever inward, and to bring the damper to bear against the inner surface of the head. Instead of connecting the damper E to a double-armed lever, 55 $a b$, however, as shown in the drawings, other means might be used for operating the damper, such, for instance, as a cam-slide; and I do not wish to confine myself to the precise mechanism shown in the drawings. Any suitable mechanism may be substituted which enables the performer to throw the damper in or out of action, or to cause the same to bear with more or less pressure against the head while he is 60 playing.

The neck G of my banjo is attached to the rim C, so that it can be readily fastened and unfastened and that the banjo can be packed up in a comparatively small space. This purpose is effected by the following means: To 70 the under surface of the neck, at its inner end, is firmly secured a double-hook, e , Figs. 2 and 3, which can be made to catch over the inner edge of the rim and which straddles the lower branch of the rod D that supports the echo-attachment. From the inner end of the neck 75 also projects a steady-pin, d , which engages with a hole in the rim C, Fig. 2. The string-plate H is held in position by a latch, e , which engages with the outer end of the bar D, and 80 which, when the strings are loose, can be readily thrown back out of gear with said bar. When the string-plate is detached, the neck can be turned down so as to free the steady-pin d , and the steady-pin d and the hook e can 85 then be disengaged from the rim. When the neck is connected to the rim, as shown in Fig. 2, it is held firmly in position by the strain of the strings.

It will be readily understood that the form 90 of the hook e may be changed and other fastening devices may be substituted, which allow of fastening the neck and unfastening it with little trouble, and I do not wish to confine myself to the precise device shown in the drawings.

The head A is tightened by means of clamps I, which are composed of screws f and hooks

g. Each of these screws passes through a lug, *h*, which is firmly secured to the rim *C*, Fig. 4, and the heads of these screws are provided with nicks or grooves for the reception of a screw-driver. The hooks *g* catch over the ring *B*, to which the head is attached, and their shanks are enlarged at their inner ends and bored out and tapped to receive the screws *f*. By these means a screw-driver can be used for tightening the head, and thereby the danger of scratching the rim is avoided, and no peculiar wrench is required.

What I claim as new, and desire to secure by Letters Patent, is—

15 1. A banjo provided with a mute or echo attachment inclosed by the surrounding frame and arranged beneath the inside surface of the head of the banjo, said mute attachment being normally retained away from the inner surface 20 of the head by the action of a spring, and having an arm extending outside the banjo-frame with its free disconnected end adapted to be

depressed by pressure against the body of the performer, substantially as described.

2. The combination, with the head *A* and 25 rim *C*, of a bar, *D*, fastened in the interior of said rim, and a damper, *E*, secured to a lever, *a b*, which has its bearing in the bar *D*, substantially as and for the purpose described.

3. The combination, with the rim *C*, the bar 30 *D*, and the neck *G*, of a double hook, *c*, fastened to the neck and adapted to catch over the lower branch of the rod *D*, and of a steady-pin, *d*, fastened in the inner end of the neck and adapted to engage with a hole in the rim, substantially as and for the purpose described. 35

In testimony whereof I have hereunto set my hand and seal in the presence of two subscribing witnesses.
